Carl J. Walberg.

UNITED STATES PATENT OFFICE.

CARL J. WALBERG, OF BOVEY, MINNESOTA.

RAILROAD-SPIKE.

1,282,338.

Specification of Letters Patent. Patented Oct. 22, 1918.

Application filed November 2, 1915. Serial No. 59,270.

To all whom it may concern:

Be it known that I, CARL J. WALBERG, a citizen of the United States, residing at Bovey, in the county of Itasca and State of Minnesota, have invented certain new and useful Improvements in Railroad-Spikes, of which the following is a specification.

My invention relates to the class of driven, headed, and screw threaded fastening and 10 more particularly to a railroad spike.

The primary object of my invention is to provide a railroad spike, which, when inserted in a tie is practically incapable of accidental loosening or displacement.

15 Another object of my invention is to provide a spike of the above mentioned class which is simple in construction and will positively be retained in position without the use of detached fastening devices or the like 20 very prevalent in the prior art.

With the above and other objects in view my invention resides preferably in the construction, combination, and arrangement of parts as hereinafter set forth in the specification and illustrated in the accompanying drawing, in which—

Figure 1 is a side elevation of a railroad spike constructed in accordance with my invention,

30 Fig. 2 is a view of the same, and

Fig. 3 is a transverse sectional view taken on a line 3—3 of Fig. 1 looking in the direction of the arrows.

Fig. 4 is a vertical section of the spike, 35 taken on the line 4—4 of Fig. 1.

Similar reference characters designate similar parts throughout the various views of the drawings.

In the drawings I have illustrated a spike 40 constructed in accordance with the objects set forth above which includes a shank 1 having a head 2 on one extremity thereof, said shank being bifurcated to provide slightly spaced arms 3 and 4 having notches 5 in the outer

45 faces thereof and pointed extremities 6 and 7 respectively. The inner abutting faces of the arms 3 and 4 are normally in slightly spaced relation as shown to advantage in Fig. 3. The adjacent edges of said inner

50 faces being beveled as indicated at 8 and 9 respectively so as to facilitate insertion of the spike and spreading of the arms to prevent dislodgment of said spike. The opposite faces of the shank 1 adjacent the start-

55 ing point of the bifurcated portion of said shank are inclined downwardly as indicated

at 10 to form tapered spurs to facilitate the driving home of the spike by being driven in between the spreading arms 3 and 4. By this operation of the spurs, it is obvious the 60 spurs will fit between the arms and will in this way brace the arms against movement toward each other, thus preventing the accidental withdrawal of the spike.

As shown to advantage in Fig. 1, the retaining lug 11 formed on the head 2 extends at right angles from said shank laterally to the plane of the bifurcation therein, so that when the spike is driven home and the arms are spread, the same will spread transversely of the tie, the notches 5 engaging the grain of the wood. The driving home of the spike is very easily accomplished and its retention assured, it being understood, of course, that the lug 11 engages the base of 75 the railway rail in the usual manner.

As shown to advantage in Fig. 1 the points 6 and 7 are afforded by beveling the adjacent faces of the arms 3 and 4 as indicated at 12, thereby assisting and starting the 80 spreading of the arms during the driving process as well as serving to penetrate the wood of a tie. Further attention is directed to the manner in which the arms 3 and 4 engage the grain of a tie and it will be noted 85 that the notches 5 engage the grain of the wood. This will also prevent early rotting of the tie owing to the tearing effect usually produced by railroad spikes.

From the above description taken in connection with the accompanying drawing, it is thought that a clear and comprehensive understanding of the construction, operation and advantages of my invention may be readily gathered and while I have shown 90 and described the same as embodying a specific structure, I reserve the right to make changes therein which do not depart from the spirit and scope of the invention as claimed.

100 What I claim is:

1. A spike of the class described comprising a head, a shank projecting from said head and being bifurcated to form a pair of spaced arms, said arms having retaining 105 notches in their outer faces, the inner edges of each arm being beveled for approximately one-third the width of the arm from each side thereof, the beveled portion extending throughout the entire length of each arm, 110 said arms having their ends beveled to provide pointed extremities and means bracing

said arms against movement toward each other after the same have been driven into a support.

2. A spike of the class described, comprising a head having a shank projecting therefrom, said shank being bifurcated to form a pair of spaced arms having pointed extremities, spurs formed upon the upper portion of said shank adjacent the base of the bifurcation, said spurs being tapered throughout their entire length, upon their outer faces into a support, whereby the pointed extremities will spread the arms, and said tapered

spurs being bent inwardly between the arms in their spread condition, when the spike is 15 carried entirely by a support, whereby the fitting of the spurs between the arms will brace the arms against movement toward each other and the accidental withdrawal of the spike being in this manner prevented. 20

In testimony whereof I affix my signature in presence of two witnesses.

CARL J. WALBERG.
